UNITED STATES PATENT OFFICE.

RICHARD EISENTRAUT AND FRIEDRICH VIELER, OF DILLINGEN-SAAR, GERMANY; ASSIGNEES TO ACTIEN-GESELLSCHAFT DER DILLINGER HÜTTENWERKE, OF DILLINGEN-ON-THE-SAAR, GERMANY, A CORPORATION OF GERMANY.

STEAM-TRAP.

No. 895,990.

Specification of Letters Patent.

Patented Aug. 11, 1908.

Application filed January 16, 1908. Serial No. 411,193.

To all whom it may concern:

Be it known that we, RICHARD EISENTRAUT and FRIEDRICH VIELER, residing at Dillingen-Saar, Germany, have invented certain new and useful Improvements in Steam-Traps; and we do hereby declare the following to be a full, clear, and exact description of the invention, such as will enable others skilled in the art to which it appertains to make and use the same.

This invention relates to steam-traps in which the pressure is normally less than that of the atmosphere; and it consists in the novel construction and combination of the parts hereinafter fully described and claimed.

In the drawings, Figure 1 is a plan view of the steam-trap with the cover removed. Fig. 2 and Fig. 3 are vertical sections taken on the lines A—B and C—D—respectively 20 in Fig. 1. Fig. 4 is a vertical section through the air-valve taken on the line E—F in Fig. 1.

The casing 1 of the steam or vapor trap is provided with an inlet 2 for vapor and water, and an outlet 3 for water. It has 25 also an air-passage 4 provided with a valve 7 which opens outwardly. The valve 5 of the inlet opens inwardly, and the valve 6 of the water outlet opens outwardly. The valves 6 and 7 are held closed by the pressure of the atmosphere when the pressure in the casing 1 is below that of the atmosphere, and the inlet-valve 5 is open, that being the normal working condition.

The valve 5 is provided with a spindle 8 which is slidable in guides 10 and 11 secured to the casing 1, and this spindle is provided with a frame 9 at its middle part between the said guides.

A shaft 12 is journaled horizontally in the 40 casing 1 under the frame 9 and in suitable supports, and 21 is an arm secured on the said shaft and provided with a head 26 having a curved slot 22 concentric with the said shaft. The head 26 is slidable in the frame 45 9, and 23 is a pin which passes through the middle part of the frame 9 and engages with the curved slot 22.

The frame 9 has a vertical portion 25 for the end 24 of the head to strike against, and 50 it has an inclined portion 27 for the curved outer surface of the head to bear against and slide on.

A lever 13 is secured to the shaft 12, and is provided with a curved and slotted portion

39 at its free end. A rod 14 is pivotally connected with the part 39, and is provided with a stop 14' at its lower end. A float 15 normally rests on the stop 14' and is slideable vertically on the rod 14. A rocking-lever 16 is also secured to the shaft 12, and 17 is a weight secured on the upper part of the said rocking-lever. The cover 20 of the casing is provided with buffers or stops 18 and 19 for the weight 17 to bear against at the extremities of its movement.

The water outlet-valve 6 is an automatic valve, and it is provided with a pivoted lever 36 connected to it by a link 38. A weight 37 is secured on the other end of the lever 37, and holds the valve lightly on its seat.

The air-valve 7 is provided with a stem 34 having a beveled portion 33 at its lower end. An arm 31 is pivoted concentric with the shaft 12 and is provided with a curved slot 30.

The arm 31 has a cam 35 at its front end for raising the air-valve, and this cam has a curved surface 32 for sustaining the said valve in its raised position. An arm 28 is secured to the shaft 12 adjacent to the arm 31, and it is provided with a pin 29 which engages with the curved slot 30.

When the parts are in the positions shown in the drawings, and water enters by the inlet 2 and accumulates in the casing 1, the float 15 is raised upon the rod 14. After the float strikes the part 39 it raises the lever 13 and turns the shaft 12 in the direction of the arrow in Fig. 2. The rocking-lever 16 is moved to the right until it passes over the center line of the shaft 12, and the inlet-valve 5 is closed by the end 24 of the head 26 which strikes the part 25 and moves the valve-spindle to the right. The weight then moves the rocking-lever and shaft suddenly until the weight strikes the buffer 19. The inlet-valve is held closed by the contact of the curved head 26 with the inclined surface 27. The aforesaid movement of the shaft 12 also turns the arms 28 and 31 to the right, and opens the air-valve immediately after the inlet-valve has been closed. The water outlet-valve opens automatically as soon as atmospheric pressure is admitted to the casing 1 through the air-valve 7.

When the water level sinks the float descends and draws down the rod 14 and lever 13, thereby turning the shaft 12 in the re-

verse direction. When the rocking-lever 16 passes over the center line of the shaft 12, the weight 17 moves the lever suddenly to the left until the weight strikes the buffer 18. 5 This motion of the shaft 12 turns the arms 28 and 31 to the left and permits the air-valve 7 to close by gravity. The arm 21 is also turned to the left to release the inlet-valve, and as soon as the air-valve has closed 10 the right-hand end of the slot 22 engages with the pin 23 and moves the valve spindle to the left, thereby opening the inlet valve. The water outlet-valve closes automatically 15 as soon as the pressure inside the casing 1 is sufficiently reduced, and the weight 37 is proportioned so that the outlet-valve will close just before the inlet-valve 5 is opened.

What we claim is:

1. In a steam-trap, the combination, with 20 a closed casing, of an automatic outlet-valve for liquid at the lower part of the said casing, for an air-valve provided with a stem, a cam for raising the said stem, a shaft journaled in the said casing, a tappet-arm secured on the said 25 shaft and operating the said cam intermittently, an inlet-valve provided with a stem, a second tappet-arm secured on the said shaft and operating the stem of the said in-

let-valve intermittently, a float-lever provided with a float and secured on the said 30 shaft, and a weighted rocking-arm secured on the said shaft and operating to move it suddenly when moved across its center line.

2. In a steam-trap, the combination, with 35 a closed casing, of an inlet-valve arranged at the upper part of the said casing and provided with an operating stem having a pin, a shaft journaled in the said casing, an arm carried by the said shaft and provided with a curved slot which engages with the said pin, 40 said arm and stem having also opposed surfaces which hold the said inlet-valve closed during a portion of the stroke of the said arm, a weighted rocking-lever also carried by the said shaft and operating to turn the said 45 shaft suddenly when moved across its center line, a float-lever also carried by the said shaft, and a float operatively connected with the said float-lever.

In testimony whereof we affix our signatures, in presence of two witnesses.

RICHARD EISENTRAUT.
FRIEDRICH VIELER.
